J. R. FORDYCE,
FIREARM.
APPLICATION FILED JAN. 22, 1918.

Patented Aug. 2, 1921.

UNITED STATES PATENT OFFICE.

JOHN R. FORDYCE, OF ST. LOUIS, MISSOURI, ASSIGNOR OF ONE-HALF TO EMIL P. PIERSON, OF WASHINGTON, DISTRICT OF COLUMBIA.

FIREARM.

1,386,247.

Specification of Letters Patent. Patented Aug. 2, 1921.

Application filed January 22, 1918. Serial No. 213,141.

To all whom it may concern:

Be it known that I, JOHN R. FORDYCE, a citizen of the United States, residing at St. Louis, Missouri, have invented a certain new and useful Improvement in Firearms, of which the following is a full, clear, and exact description, such as will enable others, skilled in the art to which it appertains to make and use the same.

10 This invention relates to automatic rifles, machine guns and other easily portable firearms.

15 The automatic rifles and certain types of machine guns that are now in general use are sufficiently light in weight to permit them to be transported easily from place to place, but such guns, when loaded with ammunition, are too heavy to enable them to be supported by the arms of the user in the 20 same manner that an ordinary rifle or small caliber gun is supported during the operation of aiming and firing the same. In fact, guns of the kind referred to are equipped with a bipod, standard or other device that 25 is adapted to be rested on the ground so as to support the gun while it is being aimed and fired, and while such guns are sometimes used in making a charge on the enemy, they cannot be aimed and fired accurately 30 at such times, due to the fact that they are so heavy that they have to be supported on the hip of the user, in which position it is practically impossible to aim and fire the gun with any degree of accuracy.

35 The main object of my invention is to provide an automatic rifle, machine gun or other type of rapid fire gun which is so constructed that it can be aimed and fired accurately while the user is running, walking 40 or in such a position that it is not possible or practicable to support the gun by resting some portion of same on the ground or on a supporting structure. To this end I have devised a gun which is so constructed that 45 the weight of the gun and the supply of ammunition for the gun are borne by the shoulder of the user when the gun is being aimed and fired, the gun being provided with means arranged in proximity to the front 50 end of the barrel of the gun for actuating the mechanism that operates the gun or effects the explosion of the ammunition.

Another object is to provide an automatic rifle or other type of rapid fire gun that is 55 equipped with means for suspending the

gun and its load of ammunition from the shoulder of the user when the gun is not in use, thus leaving both hands of the user free at such times.

And still another object is to provide a 60 magazine gun that is adapted to be supported on or from the shoulder of the user with the barrel of the gun pointed forwardly when the gun is in use and which is equipped with means arranged in proximity 65 to the front end of the barrel of the gun for firing the gun and also for operating the device that is used in magazine guns for causing the first cartridge to be fed from the magazine into the firing chamber of the 70 gun. Other objects and desirable features of my invention will be hereinafter pointed out.

75 My invention is applicable to any kind of gun or fire arm which, when loaded with ammunition, is too heavy to enable the gun to be supported by the arms of the user during the operation of firing the gun, but which is sufficiently light in weight to enable the user to carry the gun from place 80 to place. It is particularly applicable, however, to automatic rifles, machine guns and other fire arms which are designed to fire a relatively large number of shots in rapid succession. My invention can be applied 85 easily to automatic rifles and other types of rapid fire guns now in general use by means of a few simple attachments or additions to such guns. Hence, it is of the utmost 90 importance at this time, as it makes it possible to convert an ordinary automatic rifle or light-weight machine gun into a fire arm that can be used effectively in making a charge, due to the fact that the user can accurately aim and fire the gun while he is 95 running. The invention can also be embodied in a gun designed to be supported or suspended from the shoulder of the user and supplied with ammunition automatically from a magazine formed integral with 100 the gun or carried on the body of the user.

I have herein illustrated my invention applied to a rapid fire gun of a type now in general use and also embodied in a gun that is adapted to be suspended from the shoulder of the user, but I wish it to be understood that the invention is not limited to any particular type of rapid fire gun, automatic rifle or machine gun, but, on the contrary, is applicable to any kind of fire arm 110

of sufficiently light weight to enable the gun and its supply of ammunition to be carried on the shoulder of the user while the gun is being aimed and fired.

5 Figure 1 of the drawings is a side elevational view, illustrating my invention applied to a type of gun now in general use.

Fig. 2 is a vertical cross-sectional view 10 through the barrel and the radiator of the gun, taken on approximately the line 2—2 of Fig. 1.

Fig. 3 is a side elevational view, illustrating a gun of the type shown in Fig. 1 provided with means for enabling the gun to 15 be suspended from the shoulder of the user when the gun is not in use.

Fig. 4 is a side elevational view, illustrating another form of my invention.

Fig. 5 is a longitudinal horizontal section 20 view, taken through the ammunition magazine of the gun shown in Fig. 4; and

Fig. 6 is a detail view of the shell feeding mechanism of the gun illustrated in Fig. 4, 25 showing how the cartridges or shells swing into a horizontal position as they approach the firing chamber of the gun.

Referring to Fig. 1 of the drawings, which illustrates my invention applied to a machine gun of a type that is now in general 30 use, A designates the stock of the gun, B designates the barrel, C designates the usual hand grip that is arranged on the underside of the part of the gun that carries the ammunition magazine A', D designates the trigger 35 that is adapted to be actuated by a finger of the user's hand so as to effect the explosion of the ammunition, and E designates a bipod or standard that is adapted to be placed on the ground so as to support the 40 weight of the gun while it is being aimed and fired under ordinary conditions. In order that the gun may be aimed accurately and fired when the user is running, walking or in such a position that it is impossible or 45 impracticable to support the gun by means of the bipod E, I have provided the gun with means whereby the user can aim and fire the gun when the gun is supported or rested on the shoulder of the user, as shown 50 in Fig. 1 of the drawings. Said means consists of a hand grip F or other suitable device arranged in proximity to the front end of the barrel of the gun which the user can grasp with one hand so as to balance 55 the gun on his shoulder and also move the gun laterally and tilt it vertically during the operation of aiming the gun, and a trigger operating mechanism arranged in proximity to said hand grip F, by means of 60 which the user can actuate the trigger D of the gun that controls the mechanism which effects the explosion of the ammunition. The trigger operating mechanism above referred to can be formed in various ways 65 without departing from the spirit of my

invention, the mechanism herein shown consisting of a rod G arranged longitudinally of the barrel of the gun and provided at its front end with a depending portion 1 that co-operates with a trigger H arranged in front of the hand grip F, said rod being provided at its rear end with a depending portion 2 that co-operates with the trigger D of the gun that actuates or governs the operation of the mechanism which effects the explosion of the ammunition. Said trigger actuating mechanism is so designed that when the user presses rearwardly on the auxiliary trigger H, the rod G will move rearwardly and exert sufficient pressure on the main trigger D of the gun to fire the gun. The rod G is preferably arranged inside of one of the air passageways 3 of the radiator I of the gun, but the particular arrangement and construction of the trigger operating mechanism is immaterial, so far as my invention is concerned, as my broad idea consists in a gun whose weight is borne by the shoulder of the user when arranged in firing position and provided with means arranged in proximity to the front end of the barrel of the gun for aiming and firing the gun, the gun being adapted to be supported on, rested on or suspended from the user's shoulder. In a gun of the particular type 95 herein shown, namely, one that is equipped with a bipod or standard E, the user can grasp the hand grip F with one hand and grasp the bipod E with the other hand during the operation of aiming and firing the 100 gun, if the user finds that he cannot control the gun accurately with one hand, but in practice I have found that a gun of the construction herein illustrated and weighing in the neighborhood of thirty pounds can be 105 aimed and fired with one hand with sufficient accuracy to make the gun a very efficient weapon when the user on whose shoulder the gun is supported is running or walking rapidly. The gun shown in Fig. 110 1 is provided with the usual means for causing the first shell or cartridge to be introduced into the firing chamber of the gun each time the magazine A' is loaded with a fresh supply of ammunition, said means consisting of a device 4 which I have shown diagrammatically as it forms no part of my invention. In order that the device 4 may be operated from the front end of the barrel of the gun and by the same hand that operates the trigger H, I have mounted the hand grip F on the gun in such a manner that it can be moved backwardly and forwardly, as indicated in broken lines in Fig. 1, so as to impart movement to a longitudinally-disposed rod 5 that is adapted to engage and actuate the device 4 which projects laterally from the left hand side of the gun, as shown in Fig. 2. Assuming that the magazine A' is full, the user first moves the hand grip F 115 120 125 130

rearwardly, so as to operate the device 4 which causes the first shell to be introduced into the firing chamber of the gun. The hand grip F is thereafter returned to its former position, in which position it remains while the user is firing the remaining shells in the magazine.

If desired, the gun can be provided with a loop J, as shown in Fig. 3, disposed so that the user can slip his arm through same. Said loop J not only tends to hold the gun steady while it is being aimed and fired, but it also serves to connect the gun to the body of the user in such a manner that the barrel of the gun can be permitted to swing downwardly after the firing ceases, thus leaving both hands of the user free.

In Fig. 4 of the drawings I have illustrated still another form of my invention wherein the magazine A² of the gun is so proportioned and designed that it can be positioned under the arm of the user. A loop J' that projects upwardly from the magazine A² serves to suspend the gun and its load of ammunition from the shoulder of the user, and the barrel of the gun is so positioned with relation to the loop J' that the barrel is enough lower than the user's face to enable the user to tilt his head slightly, and thus use the sights 6 on the barrel of the gun during the operation of aiming the gun. A hand grip F' is arranged in proximity to the front end of the barrel of the gun, and a trigger H' is provided for actuating the mechanism that effects the explosion of the ammunition, the trigger H' being provided with a tail piece that cooperates with a part G' that controls the operation of the firing pin. The gun shown in Fig. 4 is also provided with a part 4^a, shown diagrammatically, that is adapted to be actuated so as to cause the first shell to pass from the magazine into the firing chamber, and in order that said part 4^a may be operated from the front end of the barrel of the gun, I have mounted the hand grip F' in such a manner that it can be pulled rearwardly so as to impart movement to an element 5^a that actuates the device 4^a. It is immaterial what means is used for feeding the shells from the magazine into the firing chamber, but one means that can be used for this purpose consists of an endless chain carrier 7 for the shells α combined with a feeding device 8 that is actuated automatically by the recoil mechanism, so as to feed the carrier 7 forwardly one step after each shot. The carrier 7 is so constructed that the shells α normally stand in an upright position, as shown in broken lines in Fig. 4 and in full lines in Fig. 6, and means is provided for moving the pivotally mounted shell holders 7^a on the shell carrier into a horizontal position at a certain point in the path of travel of the shell carrier, so that the shells will be positioned properly when they reach the firing chamber of the gun. If desired, the gun can be provided at its rear end with a hand grip C' and also with a trigger D' for actuating the mechanism that effects the explosion of 70

A gun of the construction above described can be aimed and fired accurately by the user when the user is running; it can be cocked and operated by one hand to effect 75 the feeding of the first shell into the firing chamber, thus enabling it to be operated by a one-armed man, a thing that is hardly possible with the automatic rifles now in use; it can be suspended from the shoulder of the user when it is provided with a loop, as shown in Figs. 3 and 4, thus leaving both hands of the user free, and when constructed in the manner shown in Fig. 4, it can be carried easily and sighted accurately by the 80 user when the user is in motion.

Having thus described my invention, what I claim, and desire to secure by Letters Patent, is:

1. A magazine gun, comprising a barrel, 90 an ammunition magazine, mechanism arranged at the rear end of the barrel for effecting the explosion of the ammunition, and means located in proximity to the front end of said barrel for enabling the user to 95 aim the gun and control the operation of said explosion mechanism with the same hand when the gun is arranged in such a position that the weight of same is borne by the user's shoulder.

2. A magazine gun, comprising a barrel, an ammunition magazine, a reciprocating hand grip arranged in proximity to the front end of said barrel and adapted to be grasped by one hand of the user when the gun is 105 arranged in such a position that the weight of same is borne by the shoulder of the user, and means operated by said hand grip for causing the first shell to be fed from the magazine into the firing chamber of the gun. 110

3. A magazine gun, comprising a barrel, an ammunition magazine, a reciprocating hand grip arranged in proximity to the front end of the barrel and adapted to be 115 grasped by one hand of the user when the gun is arranged in such a position that the weight of same is borne by the shoulder of the user, means operated by said hand grip for causing the first shell to be fed from the magazine into the firing chamber of the 120 gun, and a trigger arranged in proximity to said hand grip for operating the mechanism that effects the explosion of the ammunition.

4. A magazine gun, comprising a barrel, 125 an ammunition magazine, a trigger and suitable mechanism arranged at the rear end of said barrel for effecting the explosion of the ammunition, a hand grip arranged in proximity to the extreme front end of the 130

barrel and adapted to be grasped by one hand of the user when the gun is arranged in such a position that the weight of same is borne by the shoulder of the user, and a 5 second trigger arranged in proximity to said hand grip and operatively connected with the trigger first referred to so as to enable the gun to be fired or operated by the hand which grasps the hand grip at the 10 front end of the barrel.

5. A magazine gun, comprising a barrel, an ammunition magazine arranged adjacent

the rear end of said barrel, a hand grip and trigger mechanism arranged in proximity to said magazine, a reciprocating hand grip 15 arranged adjacent the extreme front end of said barrel, a second trigger arranged in front of said reciprocating hand grip and operatively connected with the trigger first referred to, and means operated by said 20 reciprocating hand grip for causing the first shell to be fed from the magazine into the firing chamber of the gun.

JOHN R. FORDYCE.
